UNITED STATES PATENT OFFICE.

BERNHARD D. BEIDERHASE, OF NEW YORK, N. Y.

DESIGN FOR HANDLE OF SPOONS, FORKS, &c.

Specification forming part of Design No. 6,967, dated October 28, 1873; application filed October 11, 1873.
 [Term of Patent 7 years.]

To all whom it may concern:

Be it known that I, BERNHARD D. BEIDERHASE, of the city, county, and State of New York, have invented a new and Improved Design for Spoons, Forks, &c., of which the following is a specification:

The nature of my design is fully represented in the accompanying photographic illustration, to which reference is made.

a, Figure 1, is a view of the front side of the handle. Fig. 2, *b* is a view of the reverse side.

The front side is ornamented with two pairs of double raised lines, *c c*, which commence at the end or top of the handle on each side of the inclosed star *d*. These lines cross each other, and form and inclose an ornamented circle, *e*, at the bottom of which they again cross each other, and inclose the ornamented space *f*, at the bottom of which space they again cross each other, inclosing a vine *g*, and extend to the bowl or end of the handle, and terminate in a star, *h*, and in a scroll, *i*, on each side. The narrow space between the raised lines of each pair is chased or made to resemble circular links, or chain-work, from top to bottom of the handle. Beneath the circle *e*, outside the double lines *c c*, the handle is chased to represent a shell, *j*, on each side; and, also, beneath the space *f*, outside the raised lines *c c*, the chasing and ornamentation

is of similar nature. The circle *e*, near the top of the handle, is ornamented with a central device, *k*, surrounded by a succession of irregular-shaped fancy figures, *l*. The top of the handle, outside the double lines *c c*, is chased with curved lines, extending inward from the edge, as seen at *m m*. The ground of the circle which surrounds the star *d*, also the ground of the circle *e*, and of the space *f*, are frosted or "stippled," and not polished. The ornamentation on the reverse side of the handle is the same, with the exception of the circle *e*, which is plain and polished; and at the bottom, or on the bowl, the double lines *c c* cross each other, and extend down and inclose a circle, *n*, the ground of which is stippled or frosted, and on which there is a raised device, *o*; also, between the double lines *c c* there is a raised plain bar, *p*, on which is the word "sterling;" but any other lettering may be substituted therefor.

This design is intended for spoons, forks, ladle-handles, and other articles to which it may be adapted.

I claim as my invention—

The above-described design for a handle, substantially as set forth.

BERNHARD D. BEIDERHASE.
